US00D631745S

(12) **United States Design Patent**
Lawrence et al.

(10) **Patent No.:** US D631,745 S
(45) **Date of Patent:** ** Feb. 1, 2011

(54) **LID**

(75) Inventors: **Gary W. Lawrence**, Villa Park, IL (US);
Roman Forowycz, Lake Forest, IL (US)

(73) Assignee: **Clear Lam Packaging, Inc.**, Elk Grove
Village, IL (US)

(**) Term: **14 Years**

(21) Appl. No.: **29/357,640**

(22) Filed: **Mar. 15, 2010**

(51) **LOC (9) Cl.** 09-07

(52) **U.S. Cl.** D9/435

(58) **Field of Classification Search** D9/424,
D9/425, 431, 432, 434, 435, 436, 438, 455,
D9/456, 444, 445, 443; D7/392.1, 629, 391,
D7/607, 608, 622, 624.2, 624.3; 220/780,
220/256, 901, 802, 796, 784, 781; 215/352,
215/328, 256, 253, 252, 243, 237, 228, 223

See application file for complete search history.

Primary Examiner—Robert M Spear
Assistant Examiner—Rashida C McCoy

(57) **CLAIM**

The ornamental design for a lid, as shown and described.

DESCRIPTION

FIG. 1 is a top perspective view of a lid, showing our new design;

FIG. 2 is a bottom perspective view of the lid;

FIG. 3 is a top view of the lid;

FIG. 4 is a bottom view of the lid;

FIG. 5 is a left side view of the lid;

FIG. 6 is a right side view of the lid in an inverted state;

FIG. 7 is a front side view of the lid in an inverted state; and,

FIG. 8 is a back side view of the lid in an inverted state.

1 Claim, 5 Drawing Sheets
